UNITED STATES PATENT OFFICE.

JAMES G. WARREN, OF PROVIDENCE, RHODE ISLAND.

DESIGN FOR A TABLE-SERVICE.

SPECIFICATION forming part of Design No. 19,122, dated May 28, 1889.

Application filed December 5, 1887. Serial No. 257,061. Term of patent 7 years.

To all whom it may concern:

Be it known that I, JAMES G. WARREN, of Providence, in the county of Providence and State of Rhode Island, have invented and produced a new and original Design for Table-Service, of which the following is a specification, reference being had to the accompanying drawings, forming part thereof.

Figure 1 is a side view of my newly-designed table-service in the form of a vessel for holding liquids, such as tea, coffee, or milk; and Fig. 2 is a similar view of my novel design in the form of a bowl for holding sugar, for instance.

The leading and prominent features of my design consist in the body of the vessel, 3, being of the general contour of an inverted acorn—that is, with a conspicuously large base and an upwardly-tapering top, 3', joining the base and tapering from its point of connection therewith to its upper end, and there formed in the shape of a collar, 3², on which rests the cover, forming the apex of the acorn—and in the ornamental spout and handle 4, disposed vertically at the sides of the body, the spout and handle having the upper ends, 5, shaped in general like the body of the vessel reduced, and having the lower ends, 6, of such general shape, but inverted and reduced conspicuously smaller than the said upper ends, the enlarged ends of the spout and handle being connected by a spindle-like intermediate portion, 7.

The ornamental spout and handle 4 are braced in position by means of ornamental arms 8, connected with the body of the vessel and the upper enlarged ends of the spout and handle. The resting foot or stand 9 of the body is quite shallow and flares downwardly from the body of the vessel.

It is obvious that any of the ordinary and well-known articles of table-service—such as a tea, coffee, or milk pot, a sugar or slop bowl—may be made in accordance with my new design.

Having thus described my new and original design, I claim as new and desire to secure by Letters Patent—

The design for table-service herein shown and described, the same consisting of a truncated globe-shaped base resembling the cup of an acorn, an upward and inwardly curved portion surmounting the base, a cover having a truncated dome-shaped base surmounted by an elongated and pointed dome-shaped projection, the spout and handle formed of truncated globe-shaped bulbs surmounted by elongated pointed dome-shaped projections at their upper ends, and with a similar but conspicuously smaller bulb and elongated dome-shaped downward-projecting finial, as described.

JAMES G. WARREN.
